UNITED STATES PATENT OFFICE.

EDWARD T. BURROWES, OF PORTLAND, MAINE.

GAME-BOARD.

SPECIFICATION forming part of Letters Patent No. 674,729, dated May 21, 1901.

Application filed January 19, 1901. Serial No. 43,865. (No model.)

To all whom it may concern:

Be it known that I, EDWARD T. BURROWES, a citizen of the United States, residing at Portland, in the county of Cumberland and State 5 of Maine, have invented certain new and useful Improvements in Game-Boards; and I do hereby declare the following to be a full, clear, and exact description of the invention, such as will enable others skilled in the art to which it 10 appertains to make and use the same.

This invention relates to an improvement in game-boards, and is embodied in the construction and arrangement of parts presently to be described, and defined in the claims.

15 While the invention is designed as an improvement in a game-board—that is, one which can be readily handled and moved from and onto a suitable table or support, and thereby be desirable for general and family use in 20 places where large heavy structures could not be accommodated, such as the conventional billiard and pool tables; yet it is to be understood that the invention may be applied to game tables as distinguished from 25 boards.

The object of the present invention is to provide a satisfactory and convenient game-board which will embody in its structure a satisfactory, durable, and inexpensive cushion—a board which will be of light portable 30 construction and which will maintain its shape and an even playing-surface—and to provide the board with other features and improvements.

35 In Patent No. 659,809, issued to myself on the 16th day of October, 1900, is shown a type of board having thin flexible cushion-strips, the body of the board being preferably of wood. By experience it has been found that 40 the particular construction of cushion-strip was not satisfactory in some respects, and particularly in that the peculiar "English" could not be given to the balls as they engage the cushion. It was further found that the body 45 of the board would have a tendency to warp, and thereby become uneven on the playing-surface. While the board represented in said patent has been found eminently satisfactory, the present invention is designed to overcome 50 the defects or objections above stated and also to provide improvements. The invention may therefore be stated, generally, as

being an improvement in a game-board embodying in its structure a rail carrying a body and a cushion and means for preventing warping of the body, and thereby the distortion of the cushion, and for generally maintaining the proper relation between the playing-surface and the cushion, an even playing-surface, and also in the particular construction of the body with a closure for a pocket-opening adapted to such construction.

In the accompanying drawings I have shown a construction embodying the invention; but it is to be understood that various modifications and changes can be made without departing from the nature and principle of the invention.

Figure 1 is a plan view. Fig. 2 is a cross-section through the center of the board. Fig. 3 is a detail perspective view of one of the braces. Fig. 4 is an enlarged sectional view of the rail and a portion of the body, showing the manner of securing the cushion in place, a ball in dotted lines, and the far rail omitted. Fig. 5 is a detail view of one portion of the cushion-strip. Fig. 6 is a cross-section through the same. Fig. 7 is a detail perspective of one of the cover-clamps. Fig. 8 is an enlarged sectional view through a portion of the body, showing a brace in position. Fig. 9 is a similar view of a modified form. Fig. 10 is a plan view of one corner of the board, showing the rail or frame in section. Fig. 11 is a perspective view of a corner of the board. Fig. 12 is a similar view, the metal end removed and showing the bottom of the corner. Fig. 13 is a plan view, partly in section, of a pocket-cover. Fig. 14 is a longitudinal section through a rail or frame, showing the counting device. Fig. 15 is a similar view of a modified form, and Fig. 16 is a section taken through the corner of the board at one of the pocket-openings.

A designates the body of the board, which is conveniently made up of longitudinal strips *a*, having a tongue-and-groove connection and glued together. These strips are preferably of narrow construction, making a composite body.

B designates a surrounding frame or rail, which, as shown, extends above and below the body or board. The extension of the frame or rail below the body may, however,

the board is to be used for the game of billiards. This cover is made to exactly fit in 55 the opening C and is of a dimension to completely close the opening and rest on the portion c^3 of the opening. This cover is provided with a groove d' along its straight edges, in which is placed bowed springs d^2 , the bowed 60 portion of which projects normally beyond the plane of the edge of the cover and impinges against the rail when the cover is inserted in the pocket-opening, holding the cover firmly in place. Any desirable form of 65 pocket, as at D^3 , may be employed, the same being attached in the pocket-opening in any convenient manner, preferably by having its

cushion-strip and turn the covering slightly, 120 or, owing to the shape of the strip, it may be turned completely around or reversed, so as to present a new wearing-surface. When the covering E' is to be turned on the strip, so as 125 to present a new surface, it may be readily done by removing the clamps e' and again applying the same. By forming the clamps e' relatively short the cushion-strips may be forced into their grooves without the clamps interfering. The clamps occupy a position 130 at the extreme corner of the board, so that the continuity of the playing-face of the cushion is not broken.

Extending transversely through the under

posite directions from the extreme inner end of the vertical groove.

G designates a metallic retaining bar or brace, which is preferably formed of a strip of pressed steel bent back onto itself, its edges g being bent at right angles in opposite directions to form the horizontal portion of a T. The lower end of the brace is bulged or bent into a curved enlargement or bead g', while the main body of the brace between the parts g and g' are brought into intimate relation or contact. A brace of this formation possesses a large degree of strength against vertical flexure. The upper portions of the brace are forced into and are closely seated in the T-groove F and are held therein solely by frictional contact, thus avoiding the use of screws or nails. The length of the brace is slightly less than the width of the body between the side frames, there being a small space at opposite ends, so that the brace will be carried, and constitutes a part of the body independent of the frame, so that the entire strength and rigidity of the brace will act and serve to resist any warping of the body, but will allow shrinking and swelling. The vertical width of the brace G is such as to cause it to extend below the face of the body and to thereby add materially to the strength of the brace. It also forms a convenient handle or means for lifting and transporting the board.

In the drawings I have shown two of the braces above described; but it is to be understood that the number of braces will depend largely upon the size of the board. In some instances one brace will be sufficient to prevent the warping of the body. In Fig. 6 I have shown a slightly-modified form of the brace, being similar to the form above described, except the omission of the rounded or curved lower edge. I, however, wish it expressly understood that other forms of braces may be employed; but inasmuch as it is necessary to have the braces as light as possible without impairing their rigidity or strength the pressed-steel bent form has been found particularly desirable.

In the upper edge of the opposite side frames or rails B and conveniently at the center there is formed a deep longitudinal groove H, in which is placed a wire H', the same being secured in the groove at a point considerably below the top thereof by having its ends inserted in the plugs h h'. These plugs are forced into the pockets formed at the ends of the grooves and are there held either by friction or by glue, as may be desired. Intermediate the plugs h and h' is a central plug, which is secured in position by a small staple or other convenient means, as shown in Fig. 14. On opposite sides of the center plug are

is shown where the plug wire are provided with pointed projections h³, 75 which enter the rail.

The various details of construction above described may be modified and changed without departing from the invention.

Having thus described the invention, what I claim as new, and desire to secure by Letters Patent, is—

1. In a game-board, the combination with the body and surrounding frame, of a metallic brace having a portion entering the body, held therein and extending transversely across the same, substantially as described.

2. In a game-board, the combination with the body having a groove in the under face formed with lateral extensions, and a metallic brace having a portion fashioned to fit the groove and inserted in the groove, substantially as described.

3. In a game-board, the combination with a body having grooves therein, of means for preventing the warping of the body, consisting of bent metallic braces fashioned to fit and be retained in the grooves, substantially as described.

4. In a game-board, the combination with the body having substantially T-shaped grooves formed in its under face, of bent metallic braces fashioned at their upper edge to conform to the shape of the groove and inserted and held within the groove, substantially as described.

5. The combination with a body having a substantially T-shaped groove formed therein, of a metallic brace inserted in the groove, formed of bent metal having its upper edges bent outwardly, its lower or central portion formed into a curved bead and lying below the body, substantially as described.

6. The combination with a body having a T-groove therein, of a metallic brace inserted in the groove consisting of a strip of metal bent back onto itself, its edges being bent outwardly in opposite directions, substantially as described.

7. In a game-board, the combination with a body and surrounding frame, having a groove therein, of a thin metallic cushion-strip curved in cross-section having its edge inserted in the groove, and a facing or covering of textile material on the strip, substantially as described.

8. In a game-board, the combination with a body and surrounding frame, of a curved metallic cushion-strip secured to the board, and a fabric cover for the entire strip, substantially as described.

9. In a game-board, the combination with a body and surrounding frame, of a thin metallic cushion-strip, a fabric tubing surround-
